(57) **CLAIM**

The ornamental design for a footwear with large rubberized patches, as shown and described.

DESCRIPTION

FIG. 1 is a top perspective view of a footwear with large rubberized patches showing our new design;

FIG. 2 is a top plan view thereof;

FIG. 3 is a lateral side elevational view thereof;

FIG. 4 is a medial side elevational view thereof;

FIG. 5 is a rear elevational view thereof; and,

FIG. 6 is a front elevational view thereof.

The broken line showing on the drawing disclosure is for illustrative purposes only and forms no part of the claimed design.
